(57) **CLAIM**

We claim the ornamental design for the upper for a shoe, as shown and described.

DESCRIPTION

FIG. 1 is a perspective view of an upper for a shoe of the present invention.

FIG. 2 is a side view of the upper for a shoe shown in FIG. 1.

FIG. 3 is an opposite side view of the upper for a shoe shown in FIG. 1.

FIG. 4 is a top view of the upper for a shoe shown in FIG. 1.

FIG. 5 is a rear view of the upper for a shoe shown in FIG. 1; and,

FIG. 6 is a front view of the upper for a shoe shown in FIG. 1.

The broken lines below the upper show a part of the shoe that is not part of the claimed design. The broken lines included in the upper represent part of the claimed design.

1 Claim, 5 Drawing Sheets
